US0D1028556S

(12) **United States Design Patent** (10) **Patent No.:** **US D1,028,556 S**
(45) **Date of Patent:** **** May 28, 2024**

(54) **CRIB**

(71) Applicant: **ZHONGSHAN YONGDA BABY PRODUCTS CO.?LTD.**, Zhongshan (CN)

(72) Inventor: **GuangYuan Qi**, Zhongshan (CN)

(**) Term: **15 Years**

(21) Appl. No.: **29/855,763**

(22) Filed: **Oct. 6, 2022**

(51) **LOC (14) Cl.** **06-02**

(52) **U.S. Cl.**

USPC **D6/390**

(58) **Field of Classification Search**

USPC D6/331, 382, 383, 390, 391, 392, 718.26

CPC A47D 7/00; A47D 7/002; A47D 7/005;

(57) **CLAIM**

The ornamental design for a crib, as shown and described.

DESCRIPTION

FIG. 1 is a front and right side perspective view of the claimed design of a crib showing my new design;

FIG. 2 is a rear and right side perspective view of the claimed design of a crib showing my new design;

FIG. 3 is a right view of the design of FIG. 1;

FIG. 4 is a left side view of the design of FIG. 1;

FIG. 5 is a rear view of the design of FIG. 1;

FIG. 6 is a front view of the design of FIG. 1;

FIG. 7 is a top plan view of the design of FIG. 1; and,

FIG. 8 is a bottom plan view of the design of FIG. 1.

1 Claim, 8 Drawing Sheets
